WILLIAM H. CARROLL, OF JERSEY CITY, NEW JERSEY.

TRANSPORTATION-CHECK HOLDER.

No. 927,710.

Specification of Letters Patent.

Patented July 13, 1909.

Application filed April 11, 1908. Serial No. 426,533.

To all whom it may concern:

Be it known that I, WILLIAM H. CARROLL, a citizen of the United States of America, residing at Jersey City, in the county of Hudson and State of New Jersey, have invented a new and Improved Transportation-Check Holder, of which the following is a specification.

This herein-described invention discloses improvements upon the transportation check and holder shown in my prior patent No. 898,630, issued September 15th, 1908.

The invention relates to a device including a check holder, a connected baggage-engaging loop, and a catch on said loop adapted to interlock with a latch hook or hooks of the holder for securing the check to a trunk, box or other piece of baggage, the object being to provide a simple and efficient device of this character promoting convenient shipment and accurate delivery of baggage and providing safeguards against unlawful substitution of other checks thereby avoiding losses to transportation companies; the device being so inexpensive that it need be used for but one trip on railroads, steamboats or other conveyances.

The invention will first be described and then will be particularly defined in claims hereinafter set forth.

Reference is made to the accompanying drawings forming part of this specification, and in which—

Figure 1 is a front face view of the improved holder with the complete baggage check therein. Fig. 2 is a partly broken out and partly sectional vertical edge view of upper portion of the check holder, check, baggage-engaging loop and loop catch. Fig. 3 is a rear view of the holder and check with the claim coupon detached. Fig. 4 is an enlarged detail vertical sectional edge view of upper parts of the holder and check with the loop catch finally engaged with the main primary latch hook of the holder. Fig. 5 is a rear view of upper parts of the holder and check with the loop catch engaged with the holder latch-hook. Fig. 6 is a front transverse vertical sectional elevation of upper parts of the holder and check. Fig. 7 is an inner face perspective view of the loop catch; and Fig. 8 is an enlarged detail vertical sectional view showing a modified arrangement of the secondary latch hook.

The baggage check holder is a skeleton frame 1, made of sheet-metal or other ma-

terial and having a front opening bordered by side flanges 2, 2, a top flange 3, and a preferably shorter bottom flange 4, said flanges being pressed down upon the front face of the check 5, which preferably has a pendent detachable claim coupon 6. This coupon is torn off and handed to the shipper by the baggageman for use in claiming the baggage at destination. The main body and coupon portions of the check contain necessary shipping instructions with remarks indicating the condition of the baggage when shipped, and also the baggage identifying number which as shown is 9999. In order to prevent loss or delay or confused ownership should the number be blurred on or torn from the main body of the check, said number 9999 also is stamped or otherwise permanently produced upon the check holder face, and preferably upon one of the holder flanges 2, 3, 4, it being shown upon the flange 4, in Fig. 1 of the drawings. At its back or reverse side the holder frame 1 has an opening 7, through which are visible data written on the check at destination and including the date of receipt and the condition of the baggage, as shown in Fig. 3 of the drawings.

During stamping from sheet-metal or other material of the holder frame blank portions of it are slit and cut out to provide the above named opening 7, and at the same time form a flap 8 from which projects a narrower strip which later is twice bent to form the main or primary latch hook 9, and the secondary latch hook 10. In stamping the blank its upper rear portion is outwardly pressed to form a shallow pocket 11, a somewhat deeper narrower lateral pocket 12, and a still deeper pocket 13, which is preferably centrally disposed. After the hooks 9, 10, are bent to shape, the flap 8 is bent upward to lie in the shallow pocket 11 and form the inner wall of the deeper latch hook pocket 13, whereby the two hooks 9, 10, are inclosed in said pocket 13, with the free end of the primary hook 9 elastically bearing by its preferably flattened lower part closely against the outer wall of said pocket 13, while the end of the secondary hook 10 bears elastically against the flap 8, as shown in Figs. 2 and 4 of the drawings. Instead of connecting the secondary hook 10 to the extremity of the primary hook 9, a secondary hook 10*, will perform substantially the same functions if it be fastened at its lower end to the flap 8, or other inner wall of the pocket 13, and bear by its upper free end

against the inner face of the primary hook 9, as shown in Fig. 8 of the drawings.

In the outer wall of the latch-hook pocket 13, there is formed a slot having a broad 5 transversely ranging portion 14, and a communicating right angularly disposed narrower portion 15 which preferably is central relatively to the slot portion 14, thus giving the entire slot the inverted T form shown in 10 the drawings. The main body of the catch 17 is made preferably of a strip of metal doubled upon itself and having at one side or leaf a hole 18 through which is passed the opposite end of a baggage-engaging loop wire 15 19, which may have one or two or more strands. The center of the illustrated two-strand loop 19, is first bent to form the above named catch loop 16, and the wire strands are brought together to form a neck 20 sufficiently long to provide spaces 21, 21, between the inner edge of the loop 16, and the face of the catch 17, or to off-set the loop from the catch body, while the two wire strands pass upward between the two catch sides or leaves 25 which are tightly pressed to the strands to hold the wire loop 19 and its catch loop 16 securely to the body portion of the catch. The loop 16 is preferably inclined forward or downward as shown in Figs. 1, 2, 4, 7 and 8 30 of the drawings. The opposite ends of the two wire loop strands are together passed through a hole 22 in the upper edge of the holder frame and the wires then are preferably twisted together at 23, and their ends 35 then are bent laterally in opposite directions and their extremities 24 then are passed through holes 25 in the flap or inner wall 8 of the latch hook pocket and are then bent over upon said wall 8, to securely hold the wire 40 baggage-engaging loop ends to the check holder frame, as specially shown in full and dotted lines in Fig. 6 of the drawings. The frame pocket 12 accommodates the twisted and bent attaching portions 23, 24 of the wire 45 loop, and the wire end twist at 23, relieves the holes 22, 25, of most of the tearing strains incident to pulling upon the baggage-engaging loop or upon the check holder. The baggage-engaging loop may be formed otherwise 50 than of wire, and may be attached at opposite ends in any approved manner to the check holder frame and to the hook-engaging loop portion of the catch.

In using this device, the check 5 and its 55 coupon or stub 6 are properly filled out by the baggageman and the coupon is torn off and handed to the shipper. The catch 17 then is slipped through the baggage handle or cord and the catch then is laid over the holder 60 pocket 13, and the catch loop 16 is passed into the wide slot portion 14, thereby pressing inward the two latch hooks 9, 10 of Fig. 4, and the loop 16 then is pushed downward along the hook 9 beyond the slot portion 14 65 and until the outer loop side passes the point

of junction at 26 of the two hooks 9, 10, which point 26 then resumes its normal position against the outer wall of the pocket 13: The catch 17 now is drawn upward or the holder frame is pulled downward, which causes 70 passage of both primary and secondary hooks 9, 10 through the eye of the loop 16 while the neck 20 of the loop 16 enters and moves upward along the narrow part 15 of the catch slot and until said loop 16 passes the upper 75 end of the secondary hook 10 which then instantly springs away from the primary hook 9 and again resumes its normal position with its extremity bearing against the inner wall 8 of the hook pocket 13, while the catch loop 80 16 remains coupled with the primary hook 9 at final locking engagement, whereby the baggage-engaging loop catch is securely held to the check holder frame to safely fasten the check to a trunk, box or other piece of bag- 85 gage. All pulling strain on the check then is taken by opposing portions of the loop 16 and the outer pocket wall at and near the slot portion 15, and the locking hook 9 then also is practically relieved of pulling strains 90 on the check holder during transit of the baggage or while examining the check prior to delivery of the baggage to the rightful owner presenting the coupon 6 at destination. When the catch loop 16 is finally engaged 95 with the primary hook 9 as above described, any attempt to disengage the catch by sliding it downward along said hook 9 will be frustrated by entrance of the loop 16 between the primary and secondary hooks 9, 10, and it is practically impossible to release 100 the catch by prying it off without attracting attention by the consequent disfigurement of the parts.

In the modification shown in Fig. 8 of the drawings, the catch loop 16 first engages the single primary hook 9, and when said loop is moved fully outward to lock finally with said hook 9, it passes clear above the free end of the secondary hook 10*, which then prevents 110 release of the catch loop from the primary hook.

In both arrangements of primary and secondary catch-locking hooks shown in Figs. 4 and 8 of the drawings, the main body portion 115 of the locked catch 17 is held by the primary hook 9 closely to the slotted outer wall of the hook pocket 13, so as to always cover the slot 14—15, and the extremity of the primary hook 9 also extends some little distance beyond the wider slot portion 14, thereby preventing entrance through said slot portion 14 120 without noticeably disfiguring the catch, of a knife or thin tool to attempt disengagement of the catch from the locking hook, and these features of safety prevail whether the primary hook 9 alone is used, as may be done, or whether said hook 9 be used with either style of secondary hook 10, or 10* shown in 125 the drawings. The entire baggage check 130

locking devices thus are well safe-guarded to prevent detachment of the check for the purpose of unlawfully substituting another check upon the same piece of baggage.

5. The reproduction upon the check holder frame 1 of the same consecutive numeral or mark, such as 9999, appearing on the main body and coupon portions 5, 6, of the check, is not merely marking something with a plurality of identifying marks so that if one mark be blurred or mutilated another may be used. This triplication upon the original check of the identifying number or mark is an important feature of this invention. The check 5, 6, is necessarily made of paper or other substance which may be easily written upon or ink-stamped by the baggagemen, and is therefore much more liable to damage in transit than is the stronger metal frame 1. 10 It might be most inconvenient and perhaps impossible for an unknown traveler to obtain his baggage when presenting his claim coupon 6 at destination if the important identifying number or mark, say 9999, were rubbed or cut or torn from the main check portion 5, unless this number or mark appeared also on the holder frame 1, as herein described. With this identifying mark on the frame itself there need be no delay or confusion in delivering the baggage to the rightful owner or party presenting the similarly marked claim coupon, even though the main shipping check portion 5 be damaged or be wholly torn away at destination. 15 5. The check holder and check may almost instantly be removed from the baggage at destination by simply cutting or severing the wire or other loop 19, and the entire check holder, check, severed loop and the locking catch devices, may be thrown away, or the check, with or without the holder, may be preserved for filing or for future reference. 20

This invention may be modified otherwise than as above set forth within the scope of 5 one or more of the appended claims.

I claim as my invention:—

1. A transportation check and holder comprising a protective holder and a destination check retained in the holder; said holder and 0 check having a like identifying number or mark, substantially as described.
2. A transportation check and holder comprising a destination check having a detachable claim coupon, and a holder in which the 5 main body portion of the check is retained in manner permitting severance of the coupon; both the main body and coupon portions of the check and also the check holder having a like identifying number or mark, substantially as described.
3. A transportation check holder having a pocket the outer wall of which has a slot made wider at one end or part, a hook in said pocket, a baggage-engaging loop held at 10 one end to the check holder, and a catch de-
- vice held to the other end of said loop and including an inwardly projecting off-set loop adapted to enter the wider part of the holder pocket slot and engage the hook within said pocket, the neck of said hook-engaging catch 70 loop being adapted to enter the narrow part of said slot while the loop overlies the inner face of the slotted pocket wall, substantially as described.
4. A transportation check holder having a 75 pocket the wall of which has a slot made wider at one end or part, primary and secondary hooks in said pocket, a baggage-engaging loop held at one end to the check holder, and a catch device held to the other end of 80 said loop and including an inwardly projecting off-set loop adapted to enter the wider part of the holder pocket slot and engage the primary hook within the pocket, the neck of said hook-engaging catch loop being 85 adapted to enter the narrow part of said slot while the loop overlies the inner face of the slotted pocket wall; said secondary hook preventing disengagement of the catch loop from the primary hook, substantially as de- 90 scribed.
5. A transportation check holder having a pocket provided at its outer wall with a slot having wide and narrow portions, a hook in the pocket, a baggage-engaging loop fastened at one end to the holder, and a catch device fastened to the other end of the baggage-engaging loop and having an off-set loop 95 adapted to enter the slot of the holder pocket and to engage the hook in said pocket and 100 adapted also to lock behind the slotted pocket wall while the body portion of the catch covers the slot to guard the engaged catch loop and holder hook, substantially as described. 105
6. A transportation check holder having a pocket provided at its outer wall with a slot having wide and narrow portions, a hook in the pocket bearing elastically upon the inner face of the outer slotted wall of the 110 pocket and extending protectively beyond the wider portion of the wall slot, a baggage-engaging loop fastened at one end to the holder, and a catch device fastened to the other end of the baggage-engaging loop and 115 having an off-set loop adapted to enter the slot of the holder pocket and to engage the hook in said pocket and adapted also to lock behind the slotted pocket wall while the body portion of the catch covers the slot, sub- 120 stantially as described.
7. A transportation check holder having a pocket provided at its outer wall with a slot having wide and narrow portions, a hook in the pocket, a wire baggage-engaging loop 125 fastened at one end to the holder frame, and a catch device comprising opposed leaves or plates between which the other end of the wire baggage-engaging loop is confined, said catch including an inwardly projecting off- 130

set loop formed of the baggage-engaging loop wire and adapted to enter the slot of the holder pocket and to engage the hook in said pocket while locking behind the slotted pocket wall, substantially as described.

8. A transportation check holder having a pocket provided at its outer wall with a slot having wide and narrow portions, primary and secondary hooks in the pocket, a baggage-engaging loop fastened at one end to the holder, and a catch device fastened to the other end of the baggage-engaging loop and having an off-set loop adapted to engage the primary hook within the pocket while also locking behind the slotted pocket wall, said catch also having a body portion overlying said pocket wall slot when the loop is engaged with the primary hook, said secondary hook preventing disengagement of the catch loop from the primary hook, substantially as described.

9. A transportation check holder having a pocket provided at its outer wall with a slot having wide and narrow portions, a hook in the pocket, a two-strand wire baggage-engaging loop fastened at one end to the holder, and a catch device at the other end of said baggage-engaging loop and comprising two leaves or plates one having a hole through which passes the neck of an off-set loop formed at the bend of the two-strand wire loop and adapted to engage the hook, said wire strands beyond the loop neck being clamped or fastened between the two leaves or plates of the catch device, substantially as described.

10. A transportation check holder having a pocket provided at its outer wall with a slot having wide and narrow portions, a hook in the pocket, a two-strand wire baggage-engaging loop fastened at one end to the holder by passing at end parts through an opening 22 thereof and thence diverging laterally in opposite directions and passing through apertures 24, 24 of the inner pocket wall and bent at extremities over said wall, and a catch device held to the other end of said two-strand wire loop and having an off-set loop adapted to enter the pocket wall slot and to engage the hook in said pocket, substantially as described.

11. A transportation check holder having a pocket provided at its outer wall with a slot having wide and narrow portions, a hook in the pocket, a two-strand wire baggage-engaging loop fastened at one end to the holder by passing at end parts through an opening 22 thereof, said wire end parts being twisted together at 23, and thence diverging laterally in opposite directions and passing through apertures 24, 24, of the inner pocket wall and bent at extremities over said wall, and a catch device held to the other end of said two-strand wire loop and having an off-set loop adapted to enter the pocket wall slot and to engage the hook in said pocket, substantially as described.
